UNITED STATES PATENT OFFICE.

GEORGE M. WALTERS, OF PLEASANTVILLE, NEW JERSEY, ASSIGNOR OF ONE-HALF TO
HARRY HERREN POSTOLL, OF ATLANTIC CITY, NEW JERSEY.

IGNITION LOCK.

Application filed March 14, 1921. Serial No. 452,178.

To all whom it may concern:

Be it known that I, GEORGE M. WALTERS, a citizen of the United States, residing at the city of Pleasantville, county of Atlantic, 5 and State of New Jersey, have invented a certain new and useful Improved Ignition Lock, of which the following is a specification.

This invention relates to an ignition lock 10 and has more especial relation to an ignition lock for use upon motor vehicles.

The leading object of the present invention is to provide an ignition lock adapted to prevent the unauthorized starting of a 15 motor vehicle engine. A further object is to provide a lock of this character which may be applied to the dash-board or some other appropriate part of a motor vehicle the parts being so arranged that the device 20 can only be operated by a person familiar with a given cipher, key or combination specific to a selected device. Other and further objects relate to the provision of general combinations, arrangements and connections of parts for accomplishing the results 25 sought by the foregoing objects.

The invention consists of the improvements hereinafter described and finally claimed.

30 The nature, characteristic features and scope of the invention will be more fully understood from the following description taken in connection with the accompanying drawings forming part hereof, and in 35 which:

Fig. 1, is a view in horizontal, central section of a device embodying features of the invention.

Fig. 2, is a view in cross-section taken 40 upon the line 2—2 of Fig. 1.

Fig. 3, is a similar view taken upon the line 3—3 of Fig. 1.

Fig. 4, is a face view of the device, and

Figs. 5, 6, 7 and 8, are views in elevation 45 of details of construction hereinafter referred to.

For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously 50 arranged and organized and that my invention 55 is not limited to the precise arrangement and organization of the instrumentalities as herein shown and described.

In the drawings, 10 designates a casing of any desired material and preferably of an 60 annular configuration. This casing in practice is fitted, for instance, to the dash-board of a motor vehicle. Fixed within said casing 65 at one end thereof, as by screws 11, is a terminal block 12 of insulating material, as fiber. Fitted to such block are terminal posts 13, 14, 15, 16, 16' and 16'', see Fig. 3, of which 13 may be connected to a magneto, 14 to ground, 15 to a battery and 16 to a timer, in what is termed a "straight" sys- 70 tem and 16' and 16'' connected to coil and magneto respectively in a "dual" system. Rotatably mounted within the casing is a spindle 17 provided at one end with a switch 18, for bridging for instance, contacts 75 13—14 or 15—16 in a "straight" system at the proper time, and provided at its other end with an operating handle 19. This switch of course is insulated from spindle 17. Fixed to spindle 17 is an annular mem- 80 ber 20 provided with a plurality of radially disposed channels 21, see Fig. 3. Concentrically arranged with respect to member 20 and removably fixed to casing 10, as by a pin 22, is a ring 23. This ring is also provided 85 with a plurality of radially disposed channels 24 in register with channels 21, see Fig. 3. Spring pressed endwise shiftable bolts 25—26 are present in the channels 21—24, the functions of which will presently appear. Bolts 25 are cylindrical and bolts 26 are also cylindrical but cut away as at 27 as clearly shown in Figs. 7 and 8. Ring 23 is provided annularly with a plurality of channels 28 arranged at right angles to and 90 intersecting channels 24. Fitted to move endwise through each channel 28 is a plunger 29. Normally each plunger 29 engages with a bolt 26, see Fig. 1, to interlock member 20 with ring 23 thus preventing move- 95 ment of spindle 17. It is to be noted that the cut-away portion 27 of a bolt 26 passes through cut-away portion 30 of a plunger 29, and that the beveled part 31 of a plunger 29 engages the beveled part 32 of a bolt 26, 100 see Figs. 1 and 3. The bolts 25—26 are arranged according to a prescribed cipher, key or combination specific to each device. For 105 illustrative purposes, (see Fig. 3) three plungers 29 are required to be operated be- 110

fore spindle 17 can be moved. These are the plungers opposite the graduations 50-10, 70-14 and 25-5 as shown in Fig. 4. In this connection it will be noted that bolts 25 complementary to said plungers project between member 20 and ring 23 while in all other instances, bolts 25 and 26 abut at the division line between said member and ring. Thus if the proper plungers are depressed, 10 bolts 26 shift bolts 25 against springs 33 a sufficient distance to permit member 20 to be rotated. However depression of incorrect plungers serves to move bolts 26 into member 20 thus preventing movement of 15 member 20. Movement of plungers 29 is accomplished by means of a spring pressed finger piece 34, movable through rotatable cover plate 35. By progressively moving cover plate so the finger piece 34 comes opposite the proper "combination" numbers and pressing the finger piece to engage and move the proper plungers, bolts 26 are caused to function properly for the release 20 of member 20. 36 designates a housing carried by cover plate 35 which guides the stem 37 of finger piece 34 and also encloses spring 38 thereof. It also forms a bearing for 25 spindle 17. With the release of member 20, the spindle may be moved so that switch 18 30 may be caused to bridge contacts 13-14 or in other words "battery" and "timer" contacts. It will be understood that in this position of the switch that the previously 35 pressed plungers remain so positioned and that with the return of the switch to bridge contacts 15-16 (magneto-ground contacts) means must be present for returning said 40 plungers to original position. A description of such means will now be given. Movably mounted with respect to member 20 and ring 23 and also movable with 45 respect to spindle 17 and in concentric relation therewith is a disc 39 peripherally provided with spaced lugs having inclined surfaces 40. Disc 39 is provided with a pin 41 as is ring 23. Connecting these pins is a coiled spring 42. Carried by cover plate 35 is a pin 43 adapted to engage with pin 41 when cover plate, by means of finger piece 48, is moved in the proper direction and move said disc 39 so that the inclined surfaces 40 of the lugs of said disc engage beneath the inclined surface 44 of the plunger heads and restore them to normal position.

Obviously the bolts 25-26 return to normal 55 position by means of springs 33. The disc 39 is slotted as at 45 to permit of said movement. Spring 42 returns disc 39 to normal 60 position. Should an unauthorized person attempt to solve the "combination" and press upon certain plungers, the owner of the device can re-set the plungers by means of the above described disc and its parts.

It will now be apparent that I have devised a novel and useful construction which 65 embodies the features of advantage enumerated as desirable in the statement of the invention and the above description and while I have in the present instance shown and described the preferred embodiment 70 thereof which has been found in practice to give satisfactory and reliable results, it is to be understood that the same is susceptible of modification in various particulars without departing from the spirit or scope 75 of the invention or sacrificing any of its advantages.

What I claim is:

1. In a device of the character stated, a 80 rotatable spindle, a member provided with radially disposed channels fixed to said spindle, a fixed ring concentric with said member provided with channels in register with the channels of said member, spring-pressed 85 pairs of bolts located in said channels for a predetermined interlocking of said member to said ring, a plunger complementary to each set of bolts for operating the same and rotatable means including a depressible finger-piece for selectively operating predetermined 90 plungers to release said member.

2. A construction as described in claim 1, characterized by means for returning said 95 plungers to normal position.

3. A construction as described in claim 1, characterized by a casing for inclosing said member and ring said casing being provided with a cipher, key or combination for determining the proper plungers to be operated.

4. A construction as described in claim 1, 100 characterized by at least some of said pairs of bolts being arranged to prevent movement of said member upon depression of plungers complementary thereto.

In witness whereof, I have hereunto 105 signed my name.

GEORGE M. WALTERS.
